BELT MILLING AND GRINDING MACHINE

Owen D. Premo, Muskegon Heights, Mich.

Application November 12, 1940, Serial No. 365,363

3 Claims. (Cl. 51—184.2)

This invention relates to milling or grinding and polishing machines, the primary object of the invention being to provide a machine designed primarily for milling or grinding and polishing the surfaces of tubular or hollow objects.

An important object of the invention is to provide a machine of this character including driving wheels and idler wheels over which an endless strip of abrasive cloth operates, the driving wheels and idler wheels being mounted in such a way that radial movement of the driving wheels will result in a relative movement of the idler wheels in the opposite direction, maintaining the strip of abrasive cloth taut at all times, and insuring the true operation of the machine.

Another object of the invention is to provide a yieldable support for the driving wheels to permit the driving wheels to move independently of each other to compensate for enlargements or irregularities which may be present on the surface under treatment.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawings:

Figure 1 is a sectional view through a grinding machine constructed in accordance with the invention.

Figure 2 is a sectional view through a tube, showing the grinding machine as positioned therein, the grinding machine being shown in end elevation.

Figure 3 is a sectional view taken on line 3—3 of Figure 2.

Figure 4 is a longitudinal sectional view through a modified form of the invention.

Figure 5 is an end elevational view of the form of grinding machine as illustrated by Figure 4 of the drawings.

Figure 6 is a sectional view taken on line 6—6 of Figure 4.

Referring to the drawings in detail, the reference character 5 designates the power shaft of the machine, and as shown, the power shaft operates in bearings formed at the ends of the tubular housing 6 which is formed with teeth 1 that mesh with the teeth of the gear 8 mounted

on the shaft 9. Thus it will be seen that when the shaft 9 is rotated, the machine will be advanced or retracted from the tubular member being ground or resurfaced.

5 A gear indicated at 10 is keyed to one end of the shaft 5, the gear 10 being in mesh with the worm 11 operated by a suitable power device not shown.

The forward end of the power shaft 5 is secured within the sleeve 11 that in turn is secured to the gear housing 12 by means of the bolts 13.

10 The gear housing 12 is provided with openings for the reception of the tubular extensions 14, which are keyed in the openings so that the tubular extensions 14 rotate with the gear housing 12. These extensions 14 are formed on the inner ends of the arms 15 that are provided with bearings 16 in which the shafts 17 operate, the shafts 17 providing supports for the wheels 18 over which the endless strip of abrasive material 19 operates.

15 Mounted on the inner ends of the shafts 17 are pinions 20 that mesh with the pinions 21 that are secured to the outer ends of the shafts 22 that operate within the extensions 14. These shafts 22 are formed with bores extending from the inner ends thereof, the bores providing seats for the shafts 23 formed on the pinions 24, the shafts 23 being splined within the bores of the shaft 22. Coiled springs indicated at 25 are mounted within the bores of the shaft 22 and have their inner ends bearing against the shaft 23. It will of course be understood that the tubular extensions 14 are splined within the gear housing 12, so that the arms 15 together with the tubular extensions 14, will be urged outwardly, under the action of the coiled spring 25.

20 As clearly shown by Figure 1 of the drawings, the inner ends of the tubular extensions 14 are formed with threads to accommodate the threads of the adjusting nuts 26 that bear against the gear housing 12. Due to this construction, it will be seen that adjustment of the arms 15, towards and away from the work, may be accomplished.

25 The pinions 24 mesh with teeth 27 formed at the inner end of the housing 6, with the result that as the gear housing 12 rotates, rotary movement will be imparted to the pinions 24, rotating the shafts 22. Rotary movement of the shafts 22 will cause a relative rotary movement of the pinions 21 that in turn rotate the pinions 20 transmitting rotary movement to the wheels 18 and strip of abrasive cloth operating thereover. As clearly

shown by Figure 2 of the drawings, the wheels 18 are supported directly opposite to each other, and between the wheels are idler wheels indicated at 27' which idler wheels are mounted on the shafts 28 that are carried by the arms 29 that in turn are mounted on the gear housing 12, the arms 29 having extensions 30 splined in openings of the housing 12. Bores are formed in the bolts 31 that secure the arms 29 within the housing 6, the bores accommodating the coiled springs 32 that bear against the shafts 33 shown as extending into the bores. The inner ends of the extensions 30 are threaded to accommodate the adjusting nuts 34, whereby the arms 29 may be adjusted with respect to the gear housing. In the adjustment shown by Figure 3 of the drawings, it will be seen that the arms 29 may move outwardly until the nuts 34 contact with the gear housing to restrict movement of the arms. This movement takes place when irregularities are encountered on the surface being treated, and which irregularities cause an inward movement of the strip of abrasive cloth and wheels over which the abrasive cloth moves and is held against the surface under treatment. Due to this construction, the endless strip of abrasive cloth is held taut at all times. It might be further stated that the idler wheels are grooved to guide the endless strip of abrasive cloth and prevent the strip from running laterally off of the wheels 18. In the drawings, I have illustrated pairs of wheels over which the strips of abrasive cloth operate, but in view of the fact that the construction of the various wheels and supports at opposite sides of the machine are identical, only the wheels at one side of the machine have been described in detail.

In the form of the invention as shown by Figure 4 of the drawings, the power shaft is indicated by the reference character 5', and the housing in which the shaft operates is indicated at 6'. The shaft 5' is provided with a gear 10' at its outer end, by means of which power is transmitted to the shaft 5'. The worm 11' meshes with the gear 10' to rotate the gear 10'.

A gearing housing indicated at 36 is mounted on the inner end of the shaft 5' to rotate therewith. The gear housing is provided with threaded openings in which the verniers are mounted, the verniers providing supports for the hollow shafts 37 on which the grinding heads 38 are mounted. Coiled springs 39 are mounted within the hollow shafts 37 and act to urge the shafts 37 and their heads 38, outwardly. The inner end of the housing 6' is formed with teeth 40 that mesh with the teeth of the pinions 41 operating at the inner end of the shaft 5'. Stub shafts 42 extend from the gears 41 and are provided with slots extending inwardly from the outer ends thereof, the slots accommodating pins 43 that extend through the shafts 37, slidably connecting the shafts 37 to the stub shafts. By adjusting the verniers, the grinding or milling heads may be properly positioned within a hollow or tubular article to be ground or milled, and irregularities encountered by the heads, during the grinding or milling operation will cause an inward movement of the heads, resulting in a true grinding or milling of the surface.

In the operation of the device, it will be seen that the machine is positioned within the member to be treated, and the power shaft is set in motion. As the power shaft rotates the gear housing the abrasive elements of the machine will be rotated accomplishing the purpose of the invention. During the grinding operation, the abrasive elements are fed through the object under treatment, by a suitable means not shown.

What is claimed is:

1. A surface treating machine, comprising a shaft housing, gear teeth formed at the inner end of the housing, a power shaft extending through the housing, a gear housing mounted at the inner end of the shaft, and having openings in the periphery thereof, a sleeve secured to the gear housing and into which one end of the power shaft extends, and is secured, said sleeve having bearings, pinions mounted in said bearings, shafts extending from said pinions, arms providing supports for surface-treating members, hollow extensions on the arms mounted within the openings of the gear housing, hollow shafts disposed within the hollow extensions, the shafts extending from the pinions being splined within the hollow shafts, coiled springs mounted within the hollow shafts and adapted to bear against the shafts of said pinions normally urging said arms and surface-treating members carried thereby, outwardly, said gear teeth at the inner end of the housing engaging said pinions and adapted to rotate the pinions and shafts connected therewith, when the power shaft rotates.

2. A machine for treating surfaces, comprising a shaft housing, gear teeth formed at the inner end of the shaft housing, a power shaft extending through the housing, a gear housing mounted at the inner end of the shaft, a sleeve extending into the gear housing and being connected to the gear housing, pinions mounted on the sleeve, shafts extending from the pinions, said pinions being in mesh with the gear teeth of the shaft housing to receive motion therefrom, means for supporting rotary surface-treating members on the gear housing, said means embodying arms and tubular extensions on the arms, tubular shafts mounted in the extensions and to which the shafts of said pinions extend, coiled springs in the tubular shafts and bearing against the pinion shafts and the outer ends of the sleeves normally urging the tubular shafts outwardly, and means for limiting the outward movement of the arms and surface-treating members carried thereby.

3. A surface treating machine, comprising a power shaft, a gear housing mounted at the inner end of the power shaft, surface treating members, arms on which said surface treating members are supported, means for supporting the arms within the gear housing, said means comprising telescoping members, and springs disposed within the telescoping members adapted to move one member with respect to the other member urging the surface treating members to their work, and means for transmitting movement of the power shaft to the surface treating members.
